United States Patent Office

Des. 194,011
Patented Nov. 6, 1962

194,011

TIRE

Michael Tiborcz, 714 W. Market St., Akron, Ohio

Filed Feb. 5, 1962, Ser. No. 68,649

Term of patent 14 years

(Cl. D90—20)

FIG. 1

FIG. 3

FIG. 4

FIG. 2

FIG. 1 is a fragmentary perspective view of a tire embodying my new design, it being understood that the portions shown in full lines are repeated throughout the circumference of the tire;

FIG. 2 is an enlarged fragmentary plan view thereof;

FIG. 3 is an enlarged sectional view taken on the line 3-3 of FIG. 2; and

FIG. 4 is a reduced side elevation of the tire.

I claim:
The ornamental design for a tire as shown.
